US00D848234S

(12) **United States Design Patent** (10) **Patent No.:** **US D848,234 S**
(45) **Date of Patent:** **** May 14, 2019**

(54) **UTILITY KNIFE**

(71) Applicant: **Milwaukee Electric Tool Corporation**,
Brookfield, WI (US)

(72) Inventors: **Scott Bublitz**, Hartland, WI (US);
Jason Crowe, Seattle, WA (US); **Wade Burch**, Wauwatosa, WI (US); **Jeffrey S. Holly**, West Bend, WI (US)

(73) Assignee: **Milwaukee Electric Tool Corporation**,
Brookfield, WI (US)

(**) Term: **14 Years**

(21) Appl. No.: **29/515,364**

(22) Filed: **Jan. 22, 2015**

Related U.S. Application Data

(63) Continuation of application No. 29/455,601, filed on May 22, 2013, now abandoned, which is a continuation of application No. 29/433,200, filed on Sep. 27, 2012, now Pat. No. Des. 686,901, which is a continuation of application No. 29/386,433, filed on Mar. 1, 2011, now Pat. No. Des. 670,551.

(57) **CLAIM**

We claim the ornamental design for a utility knife, as shown and described.

DESCRIPTION

FIG. 1 is a perspective view of a utility knife according to an embodiment of the invention.

FIG. 2 is a left side view of the utility knife shown in FIG. 1.

FIG. 3 is a right side view of the utility knife shown in FIG. 1.

FIG. 4 is a top view of the utility knife shown in FIG. 1. FIG. 5 is a bottom view of the utility knife shown in FIG. 1. FIG. 6 is a front view of the utility knife shown in FIG. 1; and,

FIG. 7 is a rear view of the utility knife shown in FIG. 1. The broken lines depict portions of the utility knife in which the design is embodied that are not considered part of the claimed design.

1 Claim, 4 Drawing Sheets
